App. 5.

UNITED STATES PATENT OFFICE

2,537,736

WINDOW LOCK

Carl G. Carlson, Chicago, Ill.

Application August 22, 1946, Serial No. 692,266

2 Claims. (Cl. 292—182)

1

This invention relates to window locks, and its principal object is to provide window locking means actuated by a member of an ordinary sash lock to lock the lower sash, or the upper and lower sashes of a window in partially open position, so as to prevent unauthorized persons from opening either the upper or lower sash from the outside of the room.

Another object is to provide window locking means which is automatically retracted from locking position, whenever the rotatable member of the sash lock is moved to its locked position.

Another object is to provide window locking means, having an extensible and contractible locking member, whereby the lock may be adapted for windows of several widths, within certain given limits.

Other objects and advantages will occur in the course of this specification and with said objects and advantages in view, this invention consists in the several novel features of construction, arrangement and combination of parts hereinafter fully set forth and more particularly defined in the appended claims.

The invention is clearly illustrated in the drawing accompanying this specification, in which:

Fig. 1 is a view partly in plan and partly in horizontal section through the upper sash and one of the window frame members, illustrating a simple form of the present invention applied thereto;

Fig. 2 is a vertical cross section taken on the line 2—2 of Fig. 1, and

Fig. 3 is a view partly in side elevation and partly in vertical, longitudinal section taken on the line 3—3 of Fig. 1.

Referring to said drawing, which is merely illustrative of a simple embodiment of the invention, the reference character 10 designates the upper sash, and 11 the lower sash of a window, and 12 designates a sash lock of common and well known construction. The member 13 of the sash lock is secured to the lower rail of the upper sash as by screws and the rotatable cam member 14 is secured to the upper rail of the lower sash by a plate 14a fastened to the sash by screws, and said cam member is formed with a cam flange 15 which may be turned under a hook member 16 on the sash lock member 13 to lock the two sashes together. The cam member 14 has a handle or finger piece 17 by which it is rotated. The exact construction of the sash lock illustrated is immaterial to the present invention, broadly considered, as long as it includes a rotatable member which can function as means for actuating the locking means disclosed herein.

2

Slidably guided in guide members 18, 19, secured to the top rail 11a of the lower sash is a rod, designated as a whole by the reference character 20, which rod extends lengthwise along the top rail of the lower sash from the sash lock to an upright member 24 of the window frame. On the end of the rod adjacent the window frame may be secured a resilient block or foot 22, preferably formed of rubber which is arranged to be impinged against the window frame to prevent the lower sash from being raised or lowered from any given open position.

On the other end of the rod is secured a cam head 23 having an upright cam flange 24 which is arranged to be encountered by the handle 17 of the cam member 14 of the sash lock whenever the cam member is turned to its fully unlocked position, and as a result the rod 20 is moved in a direction towards the window frame bringing the block or foot 22 into frictional contact therewith. A coiled compression spring 25 surrounds the rod 20 and is interposed between an enlarged part 26 of the rod and an end wall 27 of the guide member 18, and functions to yieldably thrust the rod toward the cam member 14 of the sash lock with the head 23 in position to be engaged by the handle 17 of said cam member whenever the latter is turned to its unlocked position.

The part 26 of the rod 20 may be of square or non-circular cross section and slides in a correspondingly shaped hole in an end wall of the guide member 18, whereby the rod is kept from turning so that the head 23 will always remain in upright position to be engaged by the handle 17 of the cam member of the sash lock.

The guide member 18 may be in the form of a housing to enclose the coiled spring 25, and the rod 20 may be secured to the enlargement 26 thereof by means of a threaded connection between the two members.

For locking the upper sash as well as the lower sash, the rod 20 is provided with a branch rod 28, secured thereto as by a fitting 28a and said branch rod extends at an angle to the main rod toward the adjacent stile of the upper sash, and on the end of said branch may be secured a block 29 also preferably composed of rubber or other resilient material which is impinged against said stile whenever the rod is moved toward the window frame.

When both blocks 22, 29 are impinged, one against the window frame and one against the stile of the upper sash, neither sash can be raised or lowered from any given open position.

In the present disclosure the rod 20 is made

in sections, one section 30 telescoping into the other section 31, and secured therein by a set screw 32 which is threaded in the outer section and is screwed up against the inner section to fasten the two together in any position of adjustment, thereby accommodating the device to windows of various widths.

In use, when the sash lock is locked the handle 17 occupies the position shown in dotted lines in Fig. 1, and the spring 25 yieldably holds the blocks 22, 29, spaced from the window frame and stile of the upper sash permitting either sash to be raised or lowered.

When the sash lock is partially unlocked, either sash can be partly opened, and by fully unlocking the sash lock and therewith swinging its handle into engagement with the head 23 of the rod 20, the latter is thrust toward the window frame and the two blocks 22, 29 are impinged, one against the window frame and one against the stile of the upper sash, thereby locking both sashes against movement.

If desired, the rubber blocks may be omitted and the ends of the rod and its branch rod may engage directly with the window frame and stile of the upper sash or may engage in sockets formed therein.

Having thus described my invention, it is obvious that various immaterial modifications may be made in the same without departing from the spirit of my invention; hence, I do not wish to be understood as limiting myself to the exact form, construction, arrangement and combination of parts herein shown and described or uses mentioned.

What I claim as new and desire to secure by Letters Patent is:

1. A sash lock adapted to be mounted on a double sash window structure provided with a window jamb and having a rotatable latch member on a rail of the lower sash for locking the two sashes in closed relation, comprising a bracket adapted to be mounted on the lower sash adjacent to said latch member, a rod, one end of which is slidably mounted in said bracket, said rod being adapted to extend horizontally along the rail of the lower sash to operatively engage the window jamb in the latched position of the rod, a head on the end of said rod adjacent said bracket adapted to be positioned in the path of and engageable with said latch member when the latter is in unlocked position, said head also in the unlatched position of the latch member adapted to move said rod outwardly toward the window jamb of the window structure, resil-

ient means associated with said rod and bracket operative to urge said head toward said latch member, a second bracket in which said rod is slidably carried adapted to be mounted on said lower sash adjacent the outer end of said rod, and means on the outer end of said rod for engagement with said window jamb, in the outer position of said rod, for preventing movement of the lower sash relative to said jamb.

2. A sash lock adapted to be mounted on a double sash window structure provided with a window jamb and having a rotatable latch member on a rail of the lower sash for locking the two sashes in closed relation, comprising a bracket adapted to be mounted on the lower sash adjacent to said latch member, a rod, one end of which is slidably mounted in said bracket, said rod being adapted to extend horizontally along the rail of the lower sash to operatively engage the window jamb in the latched position of the rod, a head on the end of said rod adjacent said bracket adapted to be positioned in the path of and engageable with said latch member when the latter is in unlocked position, said head also in the unlatched position of the latch member adapted to move said rod outwardly toward the window jamb, resilient means associated with said rod and bracket operative to urge said head toward said latch member, a second bracket in which said rod is slidably carried adapted to be mounted on said lower sash adjacent the outer end of said rod, means on the outer end of said rod for engagement with said window jamb, in the outer position of said rod, for preventing movement of the lower sash relative to said jamb, an extension secured at one end to said rod and extending angularly outward therefrom toward an adjacent stile of the upper sash, and means carried by the free end of said stile of the extension engageable with said upper sash for preventing relative movement between said sashes.

CARL G. CARLSON.
